US00D587267S

(12) United States Design Patent
Wang

(10) Patent No.: US D587,267 S
(45) Date of Patent: * Feb. 24, 2009

(54) EXTERNAL STORAGE DEVICE CASE

(75) Inventor: Chia-Jen Wang, Taipei Hsien (TW)

(73) Assignee: Datastore Technology Corp., Taipei Hsien (TW)

() Term: 14 Years

(21) Appl. No.: 29/303,040

(22) Filed: Jan. 31, 2008

(51) LOC (9) Cl. 14-02

(52) U.S. Cl. D14/356

(58) Field of Classification Search D14/301, D14/313, 348-9, 351-8, 363, 368, 370, 432, D14/435-6, 496, 137, 155, 167-8, 240, 242, D14/299; D3/201, 273; D13/149, 184; 361/684-686; 360/97.01; 439/136
